UNITED STATES PATENT OFFICE.

AUGUSTUS BROCKELBANK, OF NEW YORK, N. Y.

DESIGN FOR A HOOK.

SPECIFICATION forming part of Design No. 34,533, dated May 21, 1901.

Application filed April 18, 1901. Serial No. 56,521. Term of patent 14 years.

To all whom it may concern:

Be it known that I, AUGUSTUS BROCKELBANK, a subject of the King of Great Britain, and a resident of the city of New York, borough of Manhattan, in the county and State of New York, have invented and produced a new and original Design for a Hook, of which the following is a specification, reference being had to the accompanying drawings, forming a part thereof, in which—

Figure 1 is a plan view of a hook embodying the features of my design, and Fig. 2 is an edge view of the same.

The leading feature of the design consists in the formation of the body and shank sections of the hook. The body consists of opposing side members A and A', a connecting member A², and a front member A³, which is a continuation of the side member A' and crosses the shank B of the hook, terminating in a head A⁴. The shank B is a continuation

of the body member A and extends beyond the body, at an angle thereto, and at that portion of the shank where the front member A³ crosses a dip or depression B' is formed in 25 the shank.

A minor feature of the design consists in the loop or eye C, which is a portion of the shank.

Having thus described my invention, I claim as new and desire to secure by Letters Patent—

The design for a hook herein shown and described.

In testimony whereof I have signed my 35 name to this specification in the presence of two subscribing witnesses.

AUGUSTUS BROCKELBANK.
